UNITED STATES PATENT OFFICE.

WALTER H. HIMES, OF GROVE CITY, PENNSYLVANIA, ASSIGNOR TO HIMES COHEN
TRACTOR CO., OF GROVE CITY, PENNSYLVANIA.

TRACTOR-PLOW.

1,348,995.

Specification of Letters Patent.

Patented Aug. 10, 1920.

Original application filed March 1, 1919, Serial No. 280,121. Divided and this application filed June 17, 1919. Serial No. 304,818.

To all whom it may concern:

Be it known that I, WALTER H. HIMES, a citizen of the United States, residing at 420 Lincoln avenue, Grove City, county of Mercer, State of Pennsylvania, have invented certain new and useful Improvements in Tractor-Plows, of which the following is a specification.

This invention relates to improvements in tractor plows.

The main objects of this invention are:

First, to provide an improved tractor plow support or hanger means which permits lateral movement of the plow enabling it to pass an obstruction and at the same time normally hold the plow in its proper upright working position.

Second, to provide an improved plow having these advantages which is convenient to manipulate, simple in structure and at the same time strong and durable.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Figure I is a detail side elevation of a structure embodying the features of my invention, certain parts being shown conventionally for convenience in illustration.

Fig. II is a rear elevation with parts shown in broken sections.

Fig. III is a detail plan view with various parts omitted.

In the drawing similar reference characters refer to similar parts throughout the several views. In the accompanying drawing, I have illustrated only a portion of a tractor plow of the alternating type as shown in my application for Letters Patent, Serial No. 280,121, filed March 1, 1919. My present application being a division of that application in which I claim the plow adjusting means, therefore, I only show such parts of such adjusting means in this application as have particularly to do with the features to which this application is directed.

Referring to the drawing 1 represents the running gear frame and 2 the traction or driving wheels. The driving means and connections form no part of this invention and are therefore not described herein.

The plow 3 is provided with a beam 4 which is connected to the draft bar hangers 5 by the draft bars 6. The draft bars are pivoted to the hangers at 7 and to the front end of plow beam at 8. The adjusting means for raising and lowering the front end of plow beam is the subject of my said original application and is therefore not described in detail herein. The plow is raised from and lowered to the ground and supported laterally by a mechanism comprising the hanger or supporting bar 9, the supporting bar 9 having arms 10 pivoted on the rod 11 carried by the running gear frame. The arms 10 are preferably connected by the cross piece 12 to strengthen the same, the cross piece, bar and arms being preferably an integral casting, as illustrated.

The plow beam is provided with a cross arm 13 near the rear end thereof. The supporting bar has spherical bearing members 14 at its ends and the arm 13 has similar spherical bearing members 14 at its ends. Links 15 having sockets coating to these spherical bearing members are provided. These links are connected by the cross springs 16, the springs being connected to the links near the ends thereof as shown in Fig. II. The supporting and adjusting chain 17 is connected centrally to the bar 9 and to the shaft 18 whereby the plow may be raised and lowered.

The means for actuating the shaft 18 is not illustrated or described in detail as it forms no part of my invention. Manual or power means or both may be provided as desired.

With this arrangement of parts, the plows are supported to yield laterally to pass an obstruction such as a stone or stump or in turning a corner side movement is permitted and at the same time the springs return the plow to its proper position after the obstruction is passed. The plows are maintained in a vertical position even though drawn or deflected to one side.

I have illustrated and described my improvements in a simple and practical embodiment. I have not attempted to illus-

trate certain modifications and adaptations which I contemplate as I believe the disclosure made will enable those skilled in the art to which my invention relates to adapt or 5 embody the same as may be desired.

Having thus described my invention, what I claim as new and desire to secure by Letters Patent, is:

1. In a plow, the combination with the 10 running gear frame, of a plow provided with a beam, a draft means on said running gear frame connected to the front end of said beam, a cross arm at the rear of said beam, a supporting bar pivotally mounted on said 15 frame, said bar and said arm having spherical bearing members at their ends, links having bearing sockets coacting with said bearing members on said bar and arm at the ends thereof, crossed springs connected to said 20 links, an operating chain connected to said bar, and means for adjusting said chain to raise and lower the plow.
2. In a plow, the combination with the 25 running gear frame, of a plow provided with a beam, a draft means on said running gear frame connected to the front end of said beam, a cross arm on said beam, a supporting bar pivotally mounted on said frame, 30 links connecting the ends of said bar to the ends of said arm, crossed springs connected to said links, a supporting chain for said bar, and means for adjusting said chain to raise and lower the plow.
3. In a plow, the combination with the 35 running gear frame, of a plow provided with a beam, a draft means on said running gear frame connected to the front end of said beam, a cross arm on said beam, a supporting bar pivotally mounted on said frame, 40 links connecting the ends of said bar and arm, and crossed springs connected to said links.
4. In a plow, the combination with the

frame, of a plow provided with a beam, a draft means connected to the front end of 45 said beam, means for raising and lowering the front end of the said beam, a cross arm at the rear of said beam, an adjustable supporting bar mounted on the frame, links connecting the ends of said bar and arm, means 50 for yieldingly holding said links in parallel relation, and means for raising and lowering said supporting bar to raise and lower the plow.

5. In a plow, the combination with the 55 frame, of a plow provided with a beam, a draft means connected to the front end of said beam, means for raising and lowering the front end of the said beam, a cross arm 60 at the rear of said beam, an adjustable supporting bar mounted on the frame, links connecting the ends of said bar and arm, and means for raising and lowering said supporting bar to raise and lower the plow.

6. In a plow, the combination with the 65 frame, of a plow provided with a beam, a draft means connected to the front end of said beam, a cross arm at the rear of said beam, a supporting bar mounted on the frame, links connecting the ends of said 70 bar and arm, and means for yieldingly holding said links in parallel relation.

7. In a plow, the combination with the frame, of a plow provided with a beam, a draft means connected to the front end of 75 said beam, a cross arm at the rear of said beam, a supporting bar mounted on the frame, and links connecting the ends of said bar and arm.

In witness whereof I have hereunto set my 80 hand and seal in the presence of two witnesses.

WALTER H. HIMES. [L. s.]
